UNITED STATES PATENT OFFICE.

CHARLES E. WHITE, OF MOLINE, ILLINOIS, ASSIGNOR TO DEERE & MANSUR COMPANY, OF MOLINE, ILLINOIS, A CORPORATION OF ILLINOIS.

PLANTING MECHANISM.

1,236,519.

Specification of Letters Patent. Patented Aug. 14, 1917.

Application filed August 6, 1913, Serial No. 783,443. Renewed January 8, 1917. Serial No. 141,351.

To all whom it may concern:

Be it known that I, CHARLES E. WHITE, a citizen of the United States, residing at Moline, in the county of Rock Island and 5 State of Illinois, have invented certain new and useful Improvements in Planting Mechanisms, of which the following is a specification, reference being had therein to the accompanying drawing.

10 This invention relates to improvements in corn planters of the check row class, and particularly to those in the sub-class, each of which is provided with a seeding mechanism having a delivery device which includes, as 15 one of its elements, a rotatable seed plate having cells each adapted to receive a single kernel only, and a tappet controlled clutch governing the movements of said plate.

Figure 1 is a vertical sectional view taken 20 through a seed counting and separating mechanism embodying my invention.

Fig. 2 is a plan view of the seed counting and separating mechanism with the can or hopper removed and also with the housing 25 for the cut-off and knock-out devices removed.

Fig. 3 is a plan view of the seed plate.

Fig. 4 shows a portion of the seed plate on a larger scale.

30 Fig. 5 is an edge view of the same.

Fig. 6 shows a part of the plate in Fig. 5 on a larger scale.

Fig. 7 is a plan view of the plate or ring which supports the seed plate.

35 Fig. 8 is a view partly in vertical section, partly in side elevation, showing the seed plate and its supporting ring together with the cut-off and knock-out devices.

Fig. 9 is a plan view of the driving mechanism for the seed plate.

Fig. 10 is a plan of the plate which retains the horizontal driving gear in place.

Fig. 11 is a section showing the hinging of the several parts.

45 Mounted on the upper parts of a runner supporting bracket or casting 17 is a seed-holding and separating mechanism. Bolted to the casting 17 is a base plate 18. The plate is formed with a central circular recessed boss 19 which serves to support a drive or gear ring 20. The ring is provided on its lower side with bevel gear teeth adapted to mesh with the teeth of a bevel pinion 21 on a transverse seeder shaft 50 22 having a bearing at each end in a base

plate 18. The gear ring 20 is held in place by a cap plate 23, bolted to the base plate 18. Upon the upper face of the gear ring is a circular series of upwardly projecting teeth 24 for a purpose to be described. 60

26 indicates a ring plate, hinged to the base casting at 25. It lies immediately below the seed plate, to be described, and furnishes the bottom or lower closure for the seed cells. It has a large central circular 65 opening of a diameter sufficient to permit the seed-plate-driving parts to freely rotate. It is invertible, and on one of its horizontal faces it has a ring groove or continuous depression 26^a. Its other horizontal face is 70 continuous or ungrooved. Groove 26^a is concentric with the cells formed in the seeder plate and lies at a distance, radially, equal to the radial distance of the cells from the center. When the ring plate 26 is placed 75 with the grooved side upward, the cells are relatively deeper and can receive kernels of the wider sort. When it is inverted, its flat or ungrooved surface lies below the cells, and they are relatively shallower, as is desirable when seeds of the narrower sort are being planted.

27 is a ring-like casting at the bottom of the hopper.

28 is a spring latch for securing the plate 85 26 and the hopper bottom 27 together. At 28^a there is a lock of the common sort, formed of a bolt 29, pivoted to base 18, and a slotted lug at 28^b.

30 represents the hopper, box or can, with 90 cover 31. 32 is the seed plate supported on ring plate 26, and having its lower peripheral part adjacent to the inner surface of hopper bottom 27. It is provided with downward projecting lugs 33 which engage 95 with teeth 24 on gear ring 20. It has an upper part 34 with a horizontal cross bar, an outward and downward sloping part 36, and a bottom horizontal part 35, all cast in one integral piece of metal. 100

The seed cells are indicated by 37, these being recessed in the periphery of the bottom part 35 with their outer sides open. The end walls of the cells are approximately vertical, though preferably inclining 105 slightly downward and outward away from each other, see Fig. 8. The inner walls 39 are approximately parallel with the outermost circle of the plate. Each cell is intended to receive and hold a single kernel 110

of corn with its wider faces or flat surfaces vertical, and with its longitudinal axis horizontal.

The metal projections, one between each 5 of the cells and its neighbor, may be regarded as teeth, formed in the horizontal bottom part of the plate. The metal at the top of each of these teeth is slightly cut away so that each has a rearward and outward beveled surface, as at 38 which extends to, or slightly beyond, the inner edge of the cell. At the rear end of this cut away or beveled surface there is a deepened cavity or pocket 40 with a bottom surface 10 somewhat lower than the inclined surface, but being practically an extension thereof.

The under part of each tooth (between two adjacent cells) is preferably recessed or cut away, as shown at 42. Plates, each 20 having the top part, the lower part, and the intermediate tapering connecting part, above described, and having these arranged in the way shown are designed for the purpose of economizing metal used in casting them. As generally made, these seeder plates have all of their parts lying in substantially the same horizontal planes; that is to say, they are substantially flat throughout; and consequently, during the process 25 of casting, they are warped, twisted, or thrown out of shape to such an extent that a large percentage of the cost of manufacture is attributable to the defective plates which result.

30 But when the parts are arranged in relation to each other, and the entire article is shaped in the way described, the tendency to warp, twist or bend during or after casting is obviated, the strains experienced 35 when the heated metal cools being so balanced that misshaping is avoided.

The pronounced deep socket or rabbet at 40, near the rear end of each inclined surface, is so designed that provision is made 45 for the proper delivery of the "butt" kernels which are found in greater or less numbers in every charge of seed put in the hopper. These have heretofore caused a large part of the trouble experienced in 50 using automatic planting mechanisms.

The several dimensions of these "butt" kernels, respectively, vary to such an extent from the corresponding dimensions of the central kernels (those from the central part 55 of the corn ear) that difficulty has been experienced in designing a seed-separating-and-delivering plate which will accommodate itself, not only to the flat central kernels, but also to the rounder or more approximately spherical or pear-shaped kernels at the butts. When a plate is formed with the inclined top surface 38 and the terminal, deepened cavity or pocket 40, as I have provided, it still operates successfully 60 with the central kernels, or those of the flat-

ter sort, and at the same time makes novel provision for the entrance and delivery of the spherical butt kernels.

At the center of the hopper bottom there is a cap plate 45, carried by suitable bridges 70 43 and 44, cast integral therewith. It is dome shaped, with a flat curvature, and the kernels readily slip thereon gradually, outward and downward. The outer edge of this cap registers, approximately, with the 75 top circular edge of the inclined or tapering part 36 of the seed plate.

The latter is centered by means of the cap 45, it having loose engagement therewith of such nature that it is prevented from crowding in any direction, radially, toward the surrounding ring part of the hopper bottom 80 27. This centering is obtained by companion parts which loosely interengage and permit the seed plate to be separated from the 85 cap and removed without requiring the detaching of bolts or any other fixed devices. The means shown for this are an open bottom boss or flange 46 (cast integral with the underside of the cap 45) and a hollow pin, 90 stud or lug 47 cast with the plate 32, the latter fitting snugly in the boss 46, though detachable, as aforesaid, therefrom.

The base casting 18 and the main casting 17 are provided with aligned vertical openings 48, 49. In the retaining plate 26 there is also formed an opening or notch 50 which registers with the openings 48, 49. As the seed plate is rotated, the seed cells are brought over these openings and the seeds 100 pass downward through them. For positively ejecting the seeds from the cells I provide a knock-out device having a roller 51 mounted on an arm 52, which is supported by trunnions 53 resting in notches or recesses in the hopper bottom plate 27. The roller is adapted to reciprocate and partly enter the cells as they pass and to force the seeds downward. In order to prevent more than a single seed from entering one cell and being carried to the point of discharge, I provide a cut-off 54, which is supported on trunnions 55 resting in recesses in the hopper bottom plate. A spring 56 engages the knock-out and the cut-off and serves to hold 110 each of them in its lowermost position. A cap or housing 57 incloses the upper parts of the cut-off and knock-out devices and serves to hold the trunnions in place in the recesses.

When two mechanisms of the sort above described are to be mounted upon a planter at opposite sides thereof it is essential that they be connected to the driving devices in properly timed relation to each other. In 125 order to assist the workmen in properly assembling the parts I provide each pinion 21 with an arrow 58, (Fig. 9). The arrows on the two pinions are in the same plane and point in the same direction. Upon the gear 130

ring 20 I also provide arrows 59. In the construction shown, there are four times as many teeth on the gear ring as on the pinions, and therefore four arrows are provided on the ring. In assembling, it is only necessary for the workman to place the gear ring with one of its arrows in alinement with the arrow on the corresponding pinion. This will insure the proper relationship between the rings of the two mechanisms and consequently between the two seed plates, and will insure the simultaneous dropping of seeds in equal numbers from both plates.

The necessity for indicators such as those shown for insuring proper assembly of the several parts arises from the fact that the number of gear teeth on the gear wheel 20 is not the same as the number of seed cells in the plate. Without indicating means such as I have shown it would be possible for the workman to so assemble the parts that, at the end of an actuation, one of the plates would be positioned with a cell fully over the discharge passage, as shown in Fig. 8, and the other would be positioned with the cell but partly over the discharge passage, so that it would be doubtful as to whether or not the seed would be ejected.

As the seed plate is rotated, each cell receives a single seed from the mass of seeds in the hopper and carries it to the point of discharge. The cut-off 54 coöperates with the plate to prevent the passage of more than a single seed in each cell and the knock-out device 51 acts to positively eject the seeds from the cells as they pass the discharge opening. As above described, the seed plate is of a peculiar construction. The front wall of each cell is much lower than the rear wall and a sloping top surface on each tooth extends from the rear wall of one cell downward to the front wall of the next. This aids materially in the entry of seeds into the cells; such entering being facilitated, particularly as concerns approximately spherical kernels, by the deepened pockets 40, above described. The pockets permit the thicker parts of the kernels to settle down so that the cut-off 54 will slip over their top surfaces and not throw or roll them out of the cells, as has been the case in earlier seed delivering devices of this class.

I do not herein claim as a part of my present invention the marker devices whereby a proper assembly of the seed plate driving gearing is assured, these devices being described and claimed in my co-pending application for planters, Serial No. 783,444, filed August 6, 1913.

60 What I claim is:

1. In a planter, the combination of a rotary seed delivering plate having cells for separating seeds from a seed mass and moving them to a point of delivery, a horizontal supporting member for the plate, the lower

surface of the seed plate and the upper surface of the supporting member being free from inter-engaging projections, a relatively stationary wall adjacent the seeds when in said cells and toward which wall the plate tends to crowd the seeds, two vertically separable loosely inter-engaging journal elements adapted to center the seed plate relative to its vertical axis, one formed as an integral part of the seed plate and the other carried by a relatively stationary support above the plate.

2. In a corn planting mechanism adapted to separate the seeds from a seed mass and carry them singly to a point of delivery, a seed selecting and carrying plate having an upper horizontal part formed with a plate centering element adapted to engage an upward removable companion centering element above it, a lower horizontal part formed with peripheral seed cells, an intervening part connecting the two horizontal parts, and driving devices, the centering element, the two horizontal parts, the connecting part, and the driving devices all being cast integral.

3. For a corn planting mechanism of the class specified, the herein described seed selecting and delivering plate formed with the lower horizontal part having peripheral cells each adapted to receive a kernel in a vertical edgewise position, an upper horizontal part having integral therewith a plate centering device and downwardly projecting power receiving teeth, and an intermediate tapering part connecting the two horizontal parts.

4. For a planting mechanism of the class specified, a seed selecting and delivering plate formed with a lower horizontal part having peripheral cells each adapted to hold a single kernel in a vertical edgewise position, an upper horizontal part formed with a plate centering element, and an intermediate tapering part connecting the horizontal parts, in combination with an upwardly removable centering element loosely engaging the centering element on the plate.

5. In a planting mechanism of the class described, a rotatable seed plate having peripheral cells with their outer sides open and each adapted to receive a single kernel in a vertical edgewise position, each cell having a relatively low front wall, a relatively high rear wall, and an inner edge wall formed with a depressed pocket to receive a portion of the thicker part of a relatively thick kernel, the upper outer edge of the plate between each two adjacent cells being inclined uniformly from the high rear wall of one cell to the low rear wall of the next.

6. In a planting mechanism of the class specified, a rotatable seed plate provided with peripheral cells adapted to receive ker-

- nels edgewise, with intervening teeth each formed with a backward and downward inclined upper surface, with a pocket or recess at the rear end of the inclined surface 5 for receiving the thicker part of a relatively thick kernel, and with an annular wall extending upward and inward from the inner surfaces of the said recesses.
7. In a planting mechanism of the class described, a rotatable seed plate having a peripheral horizontal part at the bottom with peripheral cells each adapted to receive a single kernel vertically edgewise and an inward inclined part extending upward from the bottom horizontal part, the horizontal part being cut away or recessed at points adjacent the rear inner sides of the cells to form downwardly depressed pockets with their bottom surfaces substantially in alignment with the surface of the upward and inward inclined part of the plate.
8. In a corn planter of the class described, a seed-carrying delivering mechanism having in combination a stationary vertical wall, a single vertically fixed rotary seed plate with peripheral cells having laterally open sides adjacent the stationary wall, a non-rotary plate below the seed plate providing the bottom closure for the cells and movable to bring the top surface of the closure into higher or into lower planes, at will, to vary the depth of the cells.
9. In a corn planter of the class described, a seed-carrying and delivering mechanism 35 having in combination a stationary vertical wall, a single vertically fixed rotary seed plate with peripheral cells having laterally open sides adjacent the stationary wall, each adapted to receive a single kernel edgewise, an invertible plate below the seed-plate having a relatively high closure surface on one side and a relatively lower closure surface on the other side. 40
10. In a corn planter of the class de- 45 scribed, a seed-carrying and delivering mechanism having in combination a base, a stationary vertical wall, a single vertically fixed rotary seed plate with peripheral cells having laterally open sides adjacent to the stationary wall and each adapted to receive a single kernel edgewise vertically, a non-rotary invertible plate hinged to the base having on its horizontal faces similar supports for the seed plate and having on one 50 of said faces a surface providing a relatively high closure for the seed cells and on the opposite surface providing a relatively lower closure for the seed cells.
- In testimony whereof, I affix my signature, in presence of two witnesses. 60
- CHARLES E. WHITE.
